Primary Examiner — Catherine Tuttle(74) *Attorney, Agent, or Firm* — Finnegan, Henderson, Farabow, Garrett & Dunner, LLP(57) **CLAIM**

The ornamental design for a plastic container, as shown and described.

DESCRIPTION

FIG. 1 is a front and right perspective view of a plastic container showing my new design, the rear and right perspective view being a mirror image thereof;

FIG. 2 is a front elevation view thereof, the rear elevation view being identical thereto;

FIG. 3 is a right side elevation view thereof, the left side elevation view being identical thereto;

FIG. 4 is a bottom view thereof; and,

FIG. 5 is a top plan view thereof.

The evenly dashed lines shown in the drawings illustrate portion of the container that form no part of the claimed design. The unevenly dashed line define the boundary of the claimed design.

The embodiment of the container depicted is shaded to designate that it is opaque. In another embodiment of the design, the container is translucent.
